UNITED STATES PATENT OFFICE.

HENRY HARMAN AND FERRIN C. HARMAN, OF CUSTER CITY, OKLAHOMA.

ANTIDRIP PUMP.

Application filed January 2, 1923. Serial No. 610,134.

To all whom it may concern:

Be it known that we, HENRY HARMAN and FERRIN C. HARMAN, citizens of the United States, residing at Custer City, in the county 5 of Custer and State of Oklahoma, have invented certain new and useful Improvements in Antidrip Pumps, of which the following is a specification.

The primary object of our said invention 10 resides in the provision of a pump, wherein means is provided for providing the usual dripping of these pumps, after the pumping action has been completed, the arrangement being such as to convey the excessive fluid 15 back into the pump casing.

A further object of the invention is the provision of such a means for pumps that is comparatively simple of construction, inexpensive of manufacture or application and 20 highly useful for the purpose intended.

The nature and advantages of the invention will be better understood when the following detailed description is read in connection with the accompanying drawings, 25 the invention residing in the construction, combination, and arrangement of parts as claimed.

In the drawings forming part of this application, like numerals of reference indicate 30 similar parts in the several views, and wherein:—

Figure 1 is a fragmentary side elevational view of the conventional form of water pump, a portion of the pump casing and the 35 water outlet nozzle being shown in cross section for more clearly disclosing the preferred embodiment of our anti-drip means.

Figure 2 is a transverse cross sectional view of the outlet nozzle of the pump, and 40 taken substantially upon the line 2—2 of Figure 1.

Figure 3 is a view similar to Figure 1 for disclosing a modified form of the invention, which is in the nature of an anti-drip attachment for pumps.

Figure 4 is a top plan view of the attachment per se, and

Figure 5 is a perspective view of the rubber attaching ring employed in conjunction 50 with the present invention.

With particular reference to the drawings, there is fragmentarily shown a pump casing A being provided with the usual outlet nozzle B. In the form of the invention shown 55 in Figures 1 and 2, the lower end of the nozzle B is flared outwardly as at 5, and is

interiorly formed with a water channel 6, which channel is occasioned by forming what may be termed a neck 7 within the outlet end of this nozzle. The channel 6 has an 60 outlet opening 8 for receiving one end of a fluid conveying pipe 9, the opposite end of this pipe engaging through an opening 10 within the pump casing A.

It will at once be apparent that a pump 65 having an outlet nozzle formed as shown in Figures 1 and 2, that any drippings of the fluid will be caught in the said channel 6, which fluid will be conveyed into the pump 70 casing A through the instrumentality of the 70 pipe 9.

Now, having reference to Figures 3 to 5 inclusive, we have shown an anti-drip means for the outlet nozzles of pumps, which means is in the form of an attachment therefor. 75 In this instance, the end of the outlet nozzle is formed with an external rounded shoulder 11. The anti-drip attachment constitutes the provision of a metallic cup 12, within which is received a composition rubber ring 80 member 13.

The lower end of the cup 12 is formed with an annular channel 14, into which the lower end of the said rubber ring is compressed in a manner hereinafter described, 85 when the attachment is placed upon the outlet nozzle of the pump for rigidly maintaining the same thereon. The bottom wall 15 of the metallic cup 12 is provided with a central opening and formed within this 90 opening is a collar or sleeve 16 which effectively provides a channel 17 between the interior of the nozzle B and the said collar or sleeve. This channel 17 has communication with an outlet nipple 18 formed upon 95 the cup and to which is secured one end of a rubber tube 19, the other end of this tube engaging through an opening 20 in the pump casing A.

In the latter mentioned form of the invention, it will be seen that the attachment may be readily positioned upon the outlet end of the nozzle B, and in positioning the same thereon, the rubber ring 13 will have close engagement with the outlet nozzle, and in view of the rounded shoulders 11 upon the nozzle, one end of the rubber ring will be forced into the said channel 14 of the cup 12 for effectively maintaining the attachment upon the nozzle.

In view of the above description, it will at once be seen that we have provided means

for effectively catching, and conveying back into the well casing, the pump drippings, and this being accomplished in a comparatively simple and inexpensive manner.

5 While we have herein shown and described the preferred embodiments of the present invention, it is nevertheless to be understood that minor changes may be made therein without departing from the spirit and the 10 scope of the invention as claimed.

What we claim as new is:—

1. The combination with a pump outlet nozzle, of a channel within the outlet end thereof for receiving the pump drippings

and means for conveying the said drippings 15 from this channel to the interior of the pump casing.

2. The combination with an outlet nozzle of a pump, of a channel within the end of 20 said nozzle and adapted for receiving the drippings from said pump and a conveying pipe attached at its opposite ends to an outlet opening within the channel and to an opening within the pump casing.

In testimony whereof we affix our signatures.

HENRY HARMAN.
FERRIN C. HARMAN.
